US00D849093S

(12) **United States Design Patent** (10) **Patent No.:** **US D849,093 S**
Bull et al. (45) **Date of Patent:** **** May 21, 2019**

(54) **MONITORING CAMERA**

(71) Applicant: **Axis AB**, Lund (SE)

(72) Inventors: **David Bull**, Lund (SE); **Daniel Ahman**, Lomma (SE); **Morten Bergstrom**, Lund (SE); **Jan Ryzak**, Malmo (SE); **Mathias Walter**, Arlov (SE); **John Akesson**, Lund (SE)

(73) Assignee: **AXIS AB**, Lund (SE)

(**) Term: **15 Years**

(21) Appl. No.: **29/600,708**

(22) Filed: **Apr. 14, 2017**

(30) **Foreign Application Priority Data**

Oct. 17, 2016 (EM) 003421262

(57) **CLAIM**

The ornamental design for a monitoring camera, as shown and described.

DESCRIPTION

FIG. 1 is a perspective view of a monitoring camera in accordance with our design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a front elevational view thereof; and,

FIG. 7 is a rear elevational view thereof.

The broken lines depict portions of the monitoring camera in which the design is embodied that form no part of the claimed design.

1 Claim, 4 Drawing Sheets
